UNITED STATES PATENT OFFICE.

BERNHARD BEHR, OF DRESDEN, GERMANY.

ADJUSTING DEVICE FOR PAPER-CARRIAGES OF CALCULATING-MACHINES.

1,050,093.

Specification of Letters Patent. Patented Jan. 14, 1913.

Application filed August 28, 1911. Serial No. 646,308.

To all whom it may concern:

Be it known that I, BERNHARD BEHR, a subject of the Kingdom of Saxony, residing at 19 Hamburgerstrasse, Dresden, in the 5 Kingdom of Saxony, in the German Empire, company director, have invented certain new and useful Improvements in Adjusting Devices for Paper-Carriages of Calculating-Machines, of which the following 10 is a specification.

This invention relates to an adjusting device for the paper carriages of calculating machines of the type provided with printing mechanism. In such machines it is of great 15 importance to move the paper carriage rapidly backward and forward between a number of columns, and adjust it in any required position. For this purpose the carriage is connected by levers to a stud which is guided 20 in a slot provided in the front wall, and on releasing the hand therefrom, it automatically adjusts itself at the required position, when seized it is again released.

In the accompanying drawing, Figure 1 25 shows a part of the front wall of the machine, with the tabulator in front elevation. Fig. 2 is a plan of a form of adjusting means, the front wall being partly broken away. Figs. 3 and 4 show a gripper guide 30 in the slot of the front wall, in two different positions. Figs. 5 and 6 are sections at right angles to Figs. 3 and 4 showing the stud.

The base plate 1, of the writing device, is 35 rigidly connected to the front wall of the machine by rods 2 and 3. In the front wall 4, is provided a guiding slot 5, for the stud 10, and above the slot are provided holes 6, for the tabulator pins 7. On the inclined 40 upper bar of the front wall is provided a scale 8. The stud 10 is guided in the slot 5 by means of a slide 9. Through the stud 10 passes a spring operated pin 12 which, at its rear end, is provided with a milled conical part 13 engaging milled walls of a guideway 14.

If the stud 10 is grasped between the first and middle fingers of the left hand, and then the thumb is pressed on the pin 12, the 45 stud 10 may be moved outwardly causing the part 15, which engages pins 19 of the slide 9. Simultaneously, the conical part 13 of the pin 12, which is controlled by the spring 11, is moved out of the slot 14, so 55 that the slide can be moved to the right, or the left, in the slot 5, by means of the stud

10. On the part 15 and rigidly connected thereto, is rotatably mounted on the pin 16, the gripper plate 18, which engages with part 15 by means of spring members 17. 60 The gripper plate is provided on both sides with hooked arms. The pins 19 projecting into the part 15, prevent rotation thereof. Into the holes 6, above the slot 5, the tabulator pins 7 are inserted, and when the stud 10 is moved laterally, the corresponding hooked arm of the gripper 18 hangs above the pins 7, previously arranged according to the headings to be made, whereby the paper carriage connected to the pin 12 is 65 adjusted, at the required position (Fig. 3). If this adjustment is to be changed, the stud 10 is again seized in the manner hereinbefore described, and by pressing on the pin 12, the conical part 13 is moved out of the 70 slot 14, whereupon the gripper 18, provided on the slide 15, can be moved over the tabulator pin 7 by rotating about the pin 16 (Fig. 4), so that the carriage again becomes 75 freely movable. If it is desired that the 80 gripper 18, as soon as a large number of tabulator pins 7 have been inserted, should pass over a number of separate tabulator pins, so that the corresponding heading may 85 remain free, then the stud 10, by pressing on the pin 12, is simultaneously moved such a distance that the tabulator pins 7 remain behind the gripper 18 and the gripper arms can slide over these. Shortly before reaching 90 the required stopping position, the gripper 18 is allowed to slide back and one of the gripper arms 18 catches on the corresponding tabulator pin 7, so that the paper carriage again remains stationary.

The connection of the stud 10, or the spring operated pin 12, to the paper carriage, is effected in the following manner:— To the conical part 13 of the pin 12 there is secured, by means of an eye 12^a, a link 21 which is hinged to the lever 22. The lever 22 is pivoted to a pin 23, provided on the underside of the base plate 1. At 24, there is secured to the rod 22 a lever 25, of which the other end 26, is pivoted to a rod 27. The rod 27 is pivoted at 28, in the support 29, on the front wall 4, and its other end is connected at 30 to a rod 31, which is connected to the member 33, rigidly secured to the paper carriage, (not shown), by the pivot 32. The columns 34 and 35, secured to the base plate 1, serve to support a rail 36. To the rod 27 is connected a roller 37,

which runs on the rail 36. On a second rail 40, which is secured to the member 39, of the support 29, and at 38, to the connecting rod 2, runs a roller 41 provided on the rod 5 22. The paper carriage can be adjusted in any other suitable intermediate position outside the rider division, as the milled cone 31 can be fixed in any suitable position in its guiding slot 14, on releasing the pin 12, of 10 the stud 10. If the adjusting pins for the movement of the paper carriage retard the movement, at any position, they can be removed completely, as they are only to facilitate the frequent reciprocal movements between equal fixing points.

I claim:—

1. In combination with a paper carriage for calculating machines having printing mechanism, of a frame portion having a milled or roughened braking surface and a slideway adjacent thereto, a milled braking element engaging said surface, a block slideable in said way, a pin connected with said element and slideable in said block, a sleeve 20 on said pin, a spring normally acting to hold said sleeve and pin in normal positions to maintain said element in engagement with said braking surface, and link mechanism connecting said pin with said carriage, substantially as described.
2. In combination with a paper carriage for calculating machines having printing mechanism, of a frame portion having a milled or roughened braking surface and a slideway adjacent thereto, a milled braking element engaging said surface, a block slideable 30 in said way, a pin connected with said element and slideable in said block, a sleeve on said pin, a spring normally acting to hold said sleeve and pin in normal positions to maintain said element in engagement with said braking surface, and link mechanism connecting said pin with said carriage, substantially as described.
3. In combination with a paper carriage for calculating machines having printing mechanism, of a frame portion having a milled or roughened braking surface and a slideway adjacent thereto, a milled braking element engaging said surface, a block slideable 35 in said way, a pin connected with said element and slideable in said block, a sleeve on said pin, a spring normally acting to hold said sleeve and pin in normal positions to maintain said element in engagement with said braking surface, and link mechanism connecting said pin with said carriage, substantially as described.

able in said way, a pin connected with said element and slideable in said block, a spring for normally holding said pin in a position to engage said element with said surface, 40 and link mechanism connecting said pin with said carriage, substantially as described.

3. A device of the class described comprising in combination, a carriage, a frame 45 portion, a pin adjustably mounted on said frame portion to be moved longitudinally thereof, brakings on said pin, a spring for normally holding said braking means in an acting position to lock said pin in an adjusted position, and mechanism connecting said pin with said carriage, substantially as described.

4. A paper carriage adjusting device comprising in combination, a frame with a slide-way 55 therein, a block slideable in said way, a pin slideable in said block and having braking means to lock the block in an adjusted position, a sleeve on said pin, a spring for holding said pin and sleeve in normal positions, a spring controlled gripper on said sleeve, and tabulator pins adjustable on said frame and disposed in the path of said gripper.

In testimony whereof I have hereunto set 65 my hand in presence of two subscribing witnesses.

BERNHARD BEHR.
